UNITED STATES PATENT OFFICE.

I. W. WETMORE, OF ERIE, PENNSYLVANIA.

IMPROVED APPARATUS FOR CONDENSING OIL-VAPORS.

Specification forming part of Letters Patent No. 39,978, dated September 15, 1863.

To all whom it may concern:

Be it known that I, I. W. WETMORE, of Erie, in the county of Erie and State of Pennsylvania, have invented a new and useful Improvement on Oil-Vapor Condensers. I call the improved condenser the "Corrugated-Plate Double-Current Siphon-Condenser." And my invention consists in double upward-flowing currents of water through shallow chambers above and below the condensing and cooling surfaces; the propulsion of these currents on the principle of the siphon; the corrugation by transverse ridges of the upper metal plate; angular cross-ridges or plain breaks in the upper part of the upper water-chamber; cross-ridges in the vapor-chamber, with horizontal doors to allow the oil to pass, while they throw the vapor against the upper condensing-surface, and the adaptation of water and steam jets to this form of condenser; and I do hereby declare that the following is a clear, full, and exact description of the construction and operation of the same, reference being had to the annexed drawings, making a part of this specification, in which—

Figure I is a perspective view. Fig. II is a vertical longitudinal section through $x''x''$; Fig. III, a vertical cross-section through $z z$; Fig. IV, a vertical cross-section through $y'y'$; Fig. V, a view of the under side of sprinkler v' , Fig. IV; Fig. VI, a longitudinal section through steam-pipe G, Fig. I.

A, Fig. I, is the body of the condenser, composed of concentric boxes. The outer one is a common wooden box from seven to sixteen feet long, one and one-half to three feet wide, and about one and one-half foot high, set on a plane inclined from six to twelve inches. The inner box has wooden sides and ends about two inches thick, fitting to the sides and ends of the outer box and fastened to them by screws from the outside. The top and bottom of the inner box are of sheet metal, and there are water-chambers two or three inches deep between them and the top and bottom of the outer box. The vapor-condensing chamber is between the metal plates.

B, Fig. I, is the water-supply pipe.

L, M, N, and O, Fig. I, are stop-cocks.

C, Fig. I, is the water-discharge pipe, from two to ten feet longer than B.

P and Q, Fig. I, are connections of the discharge-pipe with the water-chambers.

M and N are connections of the supply-pipe with the water-chambers; w and v, Fig. I, stop-cocks.

D, Fig. I, is the pond or tank of water.

E, Fig. I, is the air-pump. There may be to this a small water-discharge pipe, w', Fig. IV.

F, Fig. I, is the vapor-supply pipe.

G, Fig. I, is the steam or water pipe, one-half to one inch in diameter.

H, Fig. I, is the water-pipe, one-half inch in diameter.

I I I, &c., Fig. I, are stop-cocks to draw the water from the depressions of the upper condensing-surface. This water may be drained by slight channels between the inner and outer plank of the same side, as from i to i i, Fig. II. I I I, &c., would then be omitted.

J, Fig. I, is the gas-pipe to carry off gas and uncondensed vapors.

K, Fig. I, is the oil-discharge pipe.

S S', Fig. II, is a sheet-metal condensing-surface, one and one-half to three feet wide, corrugated to fit the steps of the sides of the inner box, S T', and fastened water-tight over its sides and ends.

T T', Fig. II, is the lower condensing or cooling surface, fastened as in the last case, and forming the bottom of the inner box. The edges are turned up, as represented in Figs. III and IV, to prevent the oil from passing out if the plate be not closely fastened. The lower end may be turned up in the same way.

a b c, &c., Fig. II, represent a cross-section of ridges which rest on cleats nailed to the inside of the inner box. The purpose of these is, first, to throw the vapor against the cooling-surface and break its direct current outward to the vapor-discharge pipe, and, second, to cause the oil to drain off as soon as condensed and leave the metal surface exposed to the vapor. They are placed at first from one and one-half to three inches from the metal ridges and from one-fourth to an inch at the lower end.

e d, &c., Fig. II, are horizontal doors to check the vapor and allow the oil to flow under them.

d, Fig. II, is the hinge, of cotton drilling, nailed onto a b and e d across their entire length.

R, Fig. II, is the retort or still.

i i, &c., Fig. II, are openings of I I, &c., Fig. I, into the water-chamber.

u, Fig. I, is an end view of a small water-box, made of sheet metal. It rests on cleats *x x'*, Fig. II. Its face down the condenser toward *x'* is represented by *v'*, Fig. IV. Its under side is represented by Fig. V. Its supply-pipe is *H'*, Fig. IV, the end of which is seen in *u*, Fig. II. The water comes from a head a few feet above. This sprinkler may be below the entrance of the vapor-pipe, and so arranged as to throw the water-spray upward into the vapor toward *S*, Fig. II.

g h j, &c., Fig. II, are ridges of boards inverted and resting on cleats on the inside of the inner box. These throw the current of water against the metal plate and remove the warm water sooner than it would rise by the action of heat. Instead of these angular pieces, single pieces may be used extending from the top down as far as the line *h*.

T and *S'*, Fig. III, and *T* and *S*, Fig. IV, are cross-sections of water-chambers.

I, Fig. III, is the gas-discharge pipe.

K' is the oil-discharge pipe.

O' O'', Fig. III, represent the longitudinal section of the water-supply pipe, made of wood or iron, with a bore of about two inches.

M' N', Fig. III, are stop-cocks to regulate the supply of water from the supply-pipe to the water-chambers.

y and *O'*, Fig. III, are stop-cocks. *y* is to be closed and *O'* opened when there is a supply of water higher than the condenser; otherwise *O'* is kept closed, except when the condenser is operated as a siphon-condenser, and it is opened to admit the air and discharge the water.

C' C'' and *P' Q'*, Fig. IV, represent the longitudinal section of the discharge-pipe and its connections with the water-chambers. These are made of wood or iron.

E, Fig. IV, is a section of air-pump. (Not properly in this figure.)

v, Fig. IV, and *w*, Fig. IV and Fig. I, are stop-cocks. There will be a stop-cock in *w*, Fig. IV, to drain the water from the air-pump.

The operation is as follows: *O'*, Fig. III, is extended to a pond of water having a few feet of head above *C''*, Fig. IV. *C''* is extended to a drain for waste water. Steam-pipe *G* and water-pipe *H*, Fig. I, are closed. Stop-cocks *w*, Fig. IV, and *M' N' y*, Fig. III, are opened, and *O'*, Fig. III, and *v*, Fig. IV, are closed. The air is exhausted at *E*, Fig. IV, when the water rises in pipe *O' O'*, Fig. III, passes through *M'* and *N'*, up the water-chambers *n'*, *p'* and *m' q'*, Fig. II, and and down *C' C''* to *v*, Fig. IV. Then close stop-cock *w* and open *v*, Fig. IV, and the water will continue to flow. The current through the condenser, being entirely separate, may be checked to any extent

in either chamber while it flows through the other. In running heavy oil this device is especially useful, as the upper condensing-surface may be kept cold by a full current of water, while the lower is at such a temperature as to keep the oil flowing. The vapor passing into the condenser from the vapor-pipe will pass up and down the zigzag passages *a b c*, &c., Fig. II, to *S'*, and the residuum out of the gas-pipe *I*, Fig. III. The oil will run down from the condensing-surface and breaks *a b c*, &c., Fig. II, pass under the doors *e d*, &c., along the cooling-plate *T T'*, and out of the oil-discharge pipe. The passage of the water up through shallow water-chambers and its discharge at the upper end of the condenser operate to throw out the hottest of the water without mixing it with the fresh cold water, and thus diminishes the amount required and increases its effect in condensing. The application of the principle of the siphon enables the refiner to locate his condenser higher and nearer to the still, and thus secure the early condensation of the vapor without increasing the power required for raising the wafer. A steam-jet may be admitted into the vapor-pipe through the steam-pipe *G'*, Fig. II, or a jet of pure water may be driven down this pipe from a rose at *l*, Fig. II. The water from the under side of *u*, Fig. II, may be made to fall on the vapor as it emerges from the vapor-pipe. The water in this case is also thrown out of the front side, *x'*, Fig. II, which is represented by *v'*, Fig. IV. This supply of water for this small water-chamber may be a chemical solution, so as to treat the oil on vapor. The velocity of the water from *l*, Fig. II, and the sudden condensation would lessen the pressure on the oil in *R*, Fig. II, and facilitate evaporation. The object of the steam-jet is the same.

Instead of the air-pump, a force-pump may be used at *O''*, Fig. III, or water may be admitted at *O'*, Fig. III, to fill the condenser.

What I claim as my invention, and desire to secure by Letters Patent, is—

1. The separate upward-flowing currents above and below the vapor-chamber.
2. The propulsion of these currents on the principle of the siphon.
3. The corrugation of the upper condensing-surface.
4. The breaks of wooden angles and doors in the vapor-chamber.
5. The sprinkler *v'*, Fig. IV, all substantially as set forth, for the purposes specified.

J. W. WETMORE.
